UNITED STATES PATENT OFFICE.

OSCAR W. SMITH, OF FLAT ROCK, MICHIGAN.

BIT.

1,128,631.

Specification of Letters Patent. Patented Feb. 16, 1915.

Application filed September 28, 1914. Serial No. 863,787.

To all whom it may concern:

Be it known that I, OSCAR W. SMITH, a citizen of the United States of America, residing at Flat Rock, in the county of Wayne and State of Michigan, have invented certain new and useful Improvements in Bits, of which the following is a specification, reference being had therein to the accompanying drawings.

10 This invention relates to bridle bits and to an arrangement thereof that gives the effect of a straight driving bit under ordinary conditions but that if desired can be made to bring pressure upon the lower jaw 15 of a horse and prevent the animal from gaining control of the bit.

The invention also includes details of construction whereby the lips of the horse are not pinched or cut by the operation of the 20 device and whereby parts do not become clogged as from freezing, and severe weather.

25 The invention consists in the matters hereinafter set forth and more particularly pointed out in the appended claims.

In the drawings, Figure 1 is a view of the bridle with a bit that embodies the invention applied thereto; Fig. 2 is a view taken in cross section showing a cheek plate and its 30 method of attachment to the mouth piece; and Fig. 3 is a plan view of the bit, enlarged, taken partially in section with the movement of the cheek bar indicated in dotted lines.

35 Referring to the drawings a mouth piece 1 in the form of a straight bar has a pair of forwardly projecting ears 2. A pair of cheek plates 3 are pivoted to swing on these ears by means of pins 4 between the outer 40 end and base or root of each ear 2 so that the pressure exerted by a plunger 5 backed by a spring 6 in an end socket of the mouth piece, tends to project the cheek plate against the forward end portion of the ear 45 which acts as a shoulder or stop.

The cheek plate 3 has a forwardly projecting outturned arm 7 in which the rein ring 8 is pivoted, the latter being bent so that on a straight pull of the rein the body 50 of the rein ring extends substantially parallel to the cheek plate. The body portion of the cheek plate is outwardly rounded and inwardly recessed, the inner curved face 55 forming a cam surface against which the rounded end of the plunger bears. This

recess is continued rearwardly of the mouth piece 1 in such manner that when the cheek plate is turned in there is no tendency of the cheek plate to pinch the horse's lip in the angle that would otherwise be formed between the mouth piece and the plate.

The pivot stud 4 is herein shown as the shank of a cheek strap ring 10 by which the bit is secured to the cheek strap of the bridle in the usual manner. This disposition of the cheek strap as a pivot is not essential to the construction as the pivot pin may be separate from the ring and the latter may be arranged and disposed on the plate in any manner desired, but preferably 70 with a pivotal connection so as not to turn with the cheek plate. A suitably arranged opening or loop in the rear end of each cheek plate affords means for attaching reins while another aperture 11 in the rear 75 portion of each cheek plate provides for the attachment of either a martingale strap or an overcheck as desired.

It is to be understood that the plates are rounded so as to not injure an animal and 30 are designed to provide the necessary strength together with lightness, the essential point of the construction being that the line of pull of the reins on the forward ends of the cheek plate is sufficiently offset by 85 the resistance of the spring plunger so that the bit has the effect of an ordinary straight bit when the horse does not attempt to pull.

If, however, the horse becomes fractious or has a tendency to draw upon the bit, 90 either a slight sawing motion or hard pull will swing the cheek plates inwardly and bring sufficient pressure upon the jaw of the horse to restrain him readily. When the strain on the reins is relieved so that there 95 is only the normal driving touch, the bit resumes its normal position and operates as an ordinary bit.

One of the advantages of the device is the disposition of the connections within the 100 cheek plate and mouth piece so that they are not exposed and do not tend to become clogged or frozen. Another advantage is the arrangement of the parts so that with the bit sufficiently wide for the horse's jaw 105 the lips of the horse are not pinched in the angles between the cheek plates and mouth piece.

Obviously changes in the details of construction may be made without departing 110

from the spirit of my invention and I do not care to limit myself to any particular form or arrangement of parts.

What I claim is:—

- 5 1. A bridle bit comprising a mouth piece having forwardly extending ears, cheek plates pivoted between the ends of the ears, spring projected plungers in recesses of the end portions of the mouth piece in sliding engagement with the cheek plates for holding the latter normally against the bearing ears, and rein rings pivoted to the forward portions of the cheek plates.
- 10 2. A bridle bit comprising a mouth piece having forwardly extended ears, cheek plates pivoted between the ends of the ears, spring projected plungers in recesses of the

end portions of the mouth piece in sliding engagement with the cheek plates for holding the latter normally against the bearing ears, and rein rings pivoted to the forward portions of the cheek plates, the rein rings and connected portions of the cheek plates being oppositely offset with the centers of movement outside the line of the pivotal connection between the cheek plates and mouth piece.

In testimony whereof I affix my signature in presence of two witnesses.

OSCAR W. SMITH.
